RESILIENT RETAINER FOR DRILL STEEL

Earl B. Lear, Utica, N.Y., assignor to Chicago Pneumatic Tool Company, New York, N.Y., a corporation of New Jersey

Application September 24, 1958, Serial No. 763,052

9 Claims. (Cl. 279—19.5)

This invention relates to percussive tools such as rock drills, and more particularly to a retainer for preventing accidental removal of the drill steel or working implement from the drill.

It is common practice to provide the drill steel with a collar and the rock drill with a latch movable into and out of the path of the collar, the latch being pivotally mounted on a pin which in turn is rigidly supported by the front head of the drill. The latch, when effective, receives blows of percussion from the drill steel and usually transmits them to the supporting pin and front head. The rock drill parts which receive and transmit such impacts are subjected to frequent breakage.

An object of this invention is to absorb the shocks transmitted through the retaining latch and therefore to protect the parts from breakage and prolong the life of the rock drill.

Another object is to protect the operator against such shocks.

A further object is the provision of a shock absorbing retainer device which is convenient to manipulate, inexpensive to manufacture, simple in construction and convenient to assemble and disassemble.

A feature of this invention is a resilient bushing, comprising a body of rubberlike material interposed between the hub portion of the latch and the supporting pin, the bushing having a tendency at all times to maintain the hub in coaxial relation with the pin but being yieldable under stress to permit the axis of the hub to be offset parallel to the axis of the pin.

Other objects and features of this invention will appear from the description which follows.

In the accompanying drawings which show one form of this invention:

Fig. 1 is a longitudinal section of the front portion of a rock drill embodying this invention, showing also the rear portion of the working implement;

Fig. 2 is a fragmentary elevational view of the front head, looking from the right of Fig. 1;

Fig. 3 is a cross-section looking along the line 3—3 of Fig. 1, looking rearward as indicated by the arrows;

Fig. 4 is a side elevation of one of the washers for the retainer bolt; and

Fig. 5 is an end view of said washer looking from the right of Fig. 4.

Referring to Fig. 1, the illustrative rock drill 10 is of the type known as a demolition tool and delivers hammer blows to a working implement or drill steel 11 inserted into the lower or front end of the drill. The drill comprises the usual cylinder 12, only the front portion of which is shown, which receives a reciprocating hammer piston 13. The cylinder is sealed at its front end by a front cylinder washer 14 which connects the cylinder to the front head 15. The front cylinder washer serves to centralize the front head with respect to the cylinder and also to provide a seat for an anvil block 16 slidably mounted in the front cylinder washer. The anvil block

2

receives the blows of the hammer piston 13 and transmits them to the working implement 11.

The working implement has a hexagonal shank 17 slidably fitting a hexagonal opening 18 in a chuck bushing 19 which is rigidly supported in the front head, for example, by means of a press fit within a bore 20 in the front head 15. Adjacent the shank 17, the implement has a collar 21, which normally seats against the front extremity of the chuck bushing 19 to provide a positive stop limiting rearward movement of the implement 11. In front of the chuck bushing 19, the front head 15 is provided with a counterbore 22 which surrounds the collar 21 and permits reciprocation thereof.

Retaining means are provided for preventing the working implement 11 from being ejected from the front head. To support such retaining means, the front head 15 is provided with a pair of lateral ears 23 defining therebetween a longitudinal slot 24 open at the front extremity of the front head. A latch 25 is disposed in the slot to cooperate with the collar 21 on the working implement.

The latch has a hub portion 26 the ends of which snugly fit the sides of the front head slot 24 with lapping engagement as shown in Figs. 2 and 3. Extending rearwardly from the hub portion is a handle 27 the rear end 25 of which projects beyond the slotted part of the front head and is exposed for convenient manipulation. Extending radially inward from the hub portion, and approximately at right angles to the handle, is a stop lug 28. As seen in Figs. 1 and 3, the stop lug is interposed 30 in the path of the implement collar 21 and prevents withdrawal of the implement from the front head when the latch is in the position shown. Between the handle and lug the latch has an inclined cam face 29. Cooperating with the cam face is a plunger 31 mounted in a bore 32 in a lateral enlargement 33 on the front head 15. A spring 34 in the bore presses the pin forwardly, causing the front extremity of the pin to ride over the cam face 29 when the latch is turned about the axis of the hub 26. Normally, the plunger engages within a depression 35 in 40 the latch to yieldingly lock the latter in the position shown in Fig. 1. When the handle 27 is swung outward and forward, the plunger 31 comes out of the depression 35 and rides over the cam face 29 and finally engages the lug 28 to arrest further movement of the latch, after it has been turned almost ninety degrees from the position shown in Fig. 1. In such off-normal position, the lug 28 45 clears the collar 22 to permit removal of the working implement 11 from the front head 15 in a well-known manner.

The present invention resides in the means for pivotally supporting the hub portion 26 of the latch 25. Such means comprises a resilient bushing 36 mounted in a bore 37 in the hub 26. The bushing comprises an outer metal sleeve 38, an inner metal sleeve 39, and an intermediate cylindrical body 40 of rubberlike material such as neoprene, bonded to both sleeves and normally holding them in co-axial spaced relation. As shown in Fig. 3, the metal sleeves are co-extensive in axial length with the hub 26 and have rotative engagement at their extremities 55 with the walls of the front head slot 24. The body of neoprene, however, is recessed or spaced as at 41 a little inwardly of the ends of the bushing and, therefore, is out of engagement with the front head walls 23.

The inner sleeve 39 has a rotating fit on a pivot pin or bolt 42 which extends transversely of the front head slot 24. One end of the bolt is provided with an integral head 43 while the other end is threaded for engagement with a nut 44. The bolt is supported rigidly in a pair of split washers 45. As shown best in Figs. 4 and 5, each 60 washer is of frusto-conical shape and has a tapered peripheral surface, a cylindrical bore 47 and a radial slot 48 extending from the bore to the periphery. The tapered

peripheries engage respectively complementary tapered openings 49 formed in the ears 23 on opposite sides of the longitudinal slot 24. As shown in Fig. 3, the split washers, when assembled, taper inwardly and the large ends have engagement respectively with the nut 44 and the bolt head 43. Due to the radial slot 48, the washers are resilient and, upon tightening of the nut 44, are wedged into firm engagement with the front head recesses to firmly support the pivot pin 42 against any movement relative to the front head 15.

In operation, the rock drill or demolition tool 19 is normally held with the chuck bushing 19 pressing against the implement collar 21 and with the front end of the implement 11 pressing against the rock or other material (not shown) being drilled. The hammer piston 13 delivers blows of percussion through the anvil block 16 to the implement 11. If the operator permits the piston to reciprocate while the drill and implement are not pressed against the work, the implement 11 will be propelled toward the front extremity of the drill. In the absence of any retainer, an accident might result. However, the forward motion of the implement is arrested by the impingement of the collar 21 against the stop lug 28 on the latch 25. As a result of such impingement or impact, the latch tends to turn counterclockwise as seen in Fig. 1, but such motion is prevented by the engagement between the handle 27 and the outside of the radial enlargement 33 on the front head. The operator may inadvertently permit the hammer piston to continue to reciprocate and thereby deliver impacts through the medium of the anvil block 16, implement shank 17 and implement collar 21 to the stop lug 28. Such impacts cause stresses and strains in the latch 25, the pivot pin 42 and in the front head ears 23 which serve as bearings for the pin. The repetition of such strains has a tendency to set up fatigue failure with the liability of breakage of the latch 25, pivot pin 42 or the front head ears 23, in the absence of any means for counteracting or absorbing such shocks. Breakage of any of these parts could occur as a result of the operator's failure to hold the rock drill pressed against the implement, thereby permitting the latter to strike the latch as previously mentioned and also as a result of the operator's efforts to use the latch as a percussive means for pulling a stuck implement out of a drill hole. In accordance with the present invention, the shocks are absorbed by the neoprene material 41 which permits the hub portion 26 of the latch to move laterally to offset its axis relative to the pin 42. The recesses 41 at the ends of the rubber cylinder 40 provide spaces for the flow of rubber to permit such axial disalignment. While the invention permits relative lateral or radial movement between the latch 25 and the pin 42, it prevents such movement between the pivot pin 42 and the front head 15. Any tendency for the pin to become loose in the front head ears 23 as a result of vibration may be offset by tightening the nut 44, thus taking up any looseness and preventing lost motion which might otherwise result in wear and breakage at the connections between the pivot pin and front head.

The resilient bushing 36 not only protects the rock drill apparatus as mentioned, but also lessens the shocks transmitted to the operator.

When the operator desires to change the implement 11, he merely swings the handle 27 away from the front head with sufficient force to overcome the yielding lock provided by plunger 31 and depression 35 until the stop lug 28 is removed from the path of the collar 22. During such movement, the hub 26 and outer sleeve 38 have a lapping engagement with the walls of front head slot 24.

What is claimed is:

1. A percussive tool comprising a front head adapted for the support of a collared working implement, a manipulative latch pivotally movable into and out of the

path of the implement collar, a cylindrical pivot pin supported by the front head and extending transversely through said latch, nut and lock washer means restraining the pivot pin from movement relative to the front head and resilient means rotatably sleeving the pin for supporting the latch for free pivotal movement about the pin and for limited movement of the latch transversely to said pin.

2. A percussive tool according to claim 1, in which the means for supporting the latch comprises a bushing having an inner cylindrical sleeve coaxial with the pin and an outer cylindrical sleeve coaxial with the inner sleeve and fixed to the latch, and resilient means interposed between the inner and outer sleeves and bonded to them.

3. A percussive tool according to claim 2, in which the resilient means is a cylindrical rubberlike body, said rubberlike body tending to hold the sleeves in axial alignment but permitting disalignment under stress.

4. A percussive tool according to claim 3, in which the front head has a longitudinal slot to receive the latch, the side walls of the slot having lapping engagement with the latch and the outer sleeve, and the rubberlike body being recessed at its ends inwardly of the inner and outer sleeves and of the side walls of the slot whereby it is normally out of contact with the latter walls and is adapted to flow axially at said recessed ends upon radial compression thereof during movement of the latch transversely of the pin.

5. A percussive tool comprising a front head having a pair of longitudinally extending ears defining a slot therebetween, a pivot pin supported by the front head and extending transversely through said ears and slot, a manipulative latch in said slot having a hub portion surrounding the pin and pivotally movable on the pin with the ends of the hub portion in lapping engagement with the sides of the slot, and resilient means interposed between the hub portion and pin to absorb shocks delivered to the latch, wherein the resilient means is a unitary bushing comprising an inner cylindrical metal sleeve member sleeving the pin in rotative relation thereto, an outer metal sleeve member surrounding the inner sleeve member in spaced coaxial relation thereto and received in said hub portion, and a cylindrical resilient body interposed between and bonded to the inner and outer sleeve members, the ends of the resilient body being recessed slightly inwardly relative to the corresponding ends of the sleeves to allow for slight axial expansion flow of the resilient body.

6. A percussive tool comprising a front head having a pair of longitudinally extending ears defining a slot therebetween, a pivot pin supported by the front head and extending transversely through said ears and slot, a manipulative latch in said slot having a hub portion surrounding the pin and pivotally movable on the pin with the ends of the hub portion in lapping engagement with the sides of the slot, and resilient means interposed between the hub portion and pin to absorb shocks delivered to the latch, characterized by a pair of washers for supporting the pin, said washers tapering toward each other and being fitted within complementary tapered recesses in the front head ears.

7. A percussive tool according to claim 6, in which each washer has a cylindrical bore and a radial slot extending from the bore to the tapered periphery, the cylindrical bore being clamped tightly about the pin upon movement of the washers toward each other.

8. In a percussive tool having a percussively driven collared drill steel slidably inserted in the front head of the tool and adapted to escape from the latter when driven unless blocked; latch means for resiliently blocking such escape, comprising a pin supported transversely of a slot having communication radially through the side wall of the front head with the drill steel, a bearing member sleeving the pin and comprising an inner cylindrical metal sleeve coaxial with and in bearing contact with

the pivot pin, an outer cylindrical metal sleeve coaxial with the inner sleeve and in spaced relation thereto, and a cylindrical resilient body in the space between the sleeves and bonded to them; a latch member having a hub in which the bearing member is received, a lug offset from the hub, and a manipulative elongated arm offset from the hub in angular spaced relation to the lug, the latch member having an operative pivoted position upon the pivot pin wherein the lug projects through the slot into the downward path of movement of the collar of the drill steel and wherein the elongated arm abuts the side area of the front head upwardly of the slot, and the resilient body affording limited radial movement to the latch member relative to the pivot pin upon contact of the collar of the drill steel with the lug; and resilient detent means yieldingly maintaining the latch member in its operative position.

9. In a percussive tool of the character described, including a front head, and a drill steel adapted to be percussively driven in an outward direction relative to the front head; a pivot pin in the front head; a latch member

pivotal into the path of movement of the drill steel so as to limit the extent of outward movement of the latter; and resilient means pivotally mounting the latch member to the pivot pin characterized by a cylindrical metal sleeve member surrounding the pivot pin in bearing relation thereto; an outer cylindrical metal sleeve in coaxial spaced relation to the inner sleeve and fixed in the latch member; and a cylindrical resilient body member substantially filling the space between the sleeves and bonded to both.
